UNITED STATES PATENT OFFICE.

CHARLES A. GASS, OF REDROCK, ARIZONA, ASSIGNOR OF ONE-HALF TO FREDERICK C. TATUM AND TOM K. RICHEY, BOTH OF TUCSON, ARIZONA.

INTERNAL-COMBUSTION ENGINE.

1,168,870.

Specification of Letters Patent. Patented Jan. 18, 1916.

Application filed April 21, 1914. Serial No. 833,361.

To all whom it may concern:

Be it known that I, CHARLES A. GASS, a citizen of the United States, residing at Redrock, county of Pinal, State of Arizona, have invented a certain new and useful Improvement in Internal-Combustion Engines, of which the following is a specification.

My invention relates to internal combustion engines of the 4-stroke cycle type and has for its object the simplification of the valve mechanism controlling the fluid contents of the cylinder. It is known that engines of this type have heretofore been constructed employing one or more reciprocating sleeves adapted to open and close a plurality of ports during the operation of the engine, but such devices are usually more or less complex; and where a single cylinder has been employed, the reciprocation thereof has been performed in a uniform manner throughout the 4-stroke cycle.

In my engine I employ a single reciprocating sleeve, mounted between a fixed cylinder and the reciprocating piston, and adapted to reciprocate through different extremes of movement during consecutive rotations of the crank shaft or in other words, during different halves of the 4-stroke cycle.

A further object of my invention is to provide the reciprocating sleeve with a plurality of ports or openings in the same plane, adapted to cooperate with an annular channel or recess in the inner surface of the fixed cylinder so that when the explosion takes place the channel will serve as a depository for carbon, thereby insuring a clean, close fitting surface between the packing rings and the cylinder on each side of the valves.

Another object of my invention is to provide a mechanism for reciprocating the sleeve which will quickly move the sleeve from one extreme of movement, when the exhaust valve is opened, to another extreme of movement, when the intake valve is opened, and then, during the remainder of the 4-stroke cycle, the movement of the sleeve is intermediate of these two extremes and the two ports referred to remain closed.

A further object is to provide compressed air for scavenging and port openings controlled by the single sleeve in conjunction with the piston for drawing the air into the crank case and after compression injecting it into the explosion chamber after the explosion. For the purpose of obtaining my

improved sleeve movement and facilitate the opening of the several ports as required, I have devised a particular arrangement of double eccentrics and pitman operable from the crank shaft and so timed as to give the sleeve the two extremes of movement desired.

I have illustrated one form of my invention in the accompanying drawings in which—

Figure 1 represents a vertical section of the engine transversely of the crank shaft; Fig. 2 represents a side elevation partially in cross-section; Figs. 3, 4, 5 and 6 are illustrative views representing the position of the parts at the end of each of the four cycles; Fig. 7 represents an enlarged view of the eccentric gear connection for reciprocating the sleeve; Fig. 8 is a side view of the same partially in section; Figs. 9 and 10 represent a modification of the eccentric mechanism for reciprocating the sleeve.

Referring to the drawings 1 represents a fixed cylinder connected with a crank case 2, which may be hinged at 3 and bolted at 4 in order that the crank and other mechanism associated therewith may be readily accessible. Any usual method of securing the engine in place may be employed. The cylinder 1 is surrounded by the usual water jacket 5 and is provided with the usual spark plug opening at 6. The cylinder is bored out of larger diameter at the bottom than at the top; that portion just under the head being of smaller internal diameter and provided with an annular channel 7 for the purpose hereinafter specified. The upper end of the cylinder is also provided with two port openings, each located in a different plane, the upper one, 8, being the exhaust port and the other, 9, being the intake port. These ports, as indicated enter the cylinder in the portion of smaller diameter above referred to. It will be noted that the intake port 9 is located below the annular channel 7 while the exhaust port opens into the cylinder above the annular channel 7. The cylinder is also provided with an auxiliary exhaust port 10 near the end of the stroke, which is adapted to be exposed by the piston, and an intake port at 11 for the entrance of air to the crank case. A bypass 12 is also provided leading from the crank case up to a port at 13 for the admission of compressed air from the crank case to the combustion chamber for the pur-

pose of scavenging with same after the explosion.

Fitting within the cylinder 1, I provide a cylindrical sleeve 14, adapted to reciprocate therein and provided with ports adapted to cooperate with the corresponding ports in the fixed cylinder 1. The upper portion of the sleeve 14 is constricted or is of less diameter than the lower portion to conform to the smaller diameter of the outer cylinder and is provided with grooves in which the packing rings 15 are placed. The packing rings 15 are located, one or more on each side of a plurality of ports or openings 16 arranged in the same plane around the entire circumference of the sleeve, which ports are adapted to cooperate with the exhaust and intake ports when the sleeve is reciprocated so as to bring the ports therein into the plane of the respective ports in the fixed cylinder. The purpose of the plurality of ports or openings 16 is to provide access of the explosive gases to the annular channels 7 when the sleeve 14 is in position to close both the intake and exhaust ports, the channels thus serving as a place of deposit for carbon which might otherwise be deposited on the smooth bore of the outer cylinder and interfere with the movement of the sleeve. It will be understood that a single annular opening could be used but for the fact that the two packing ring sections must be held together, hence the plurality of openings 16, between connecting ribs which integrally unite the two portions of the sleeve. The sleeve 14 is also provided with a port at 17 adapted to cooperate with the auxiliary exhaust port 10 of the fixed cylinder and also the ports at 18 and 19 corresponding with ports 11 and 13 of the outer cylinder for controlling inlet and exit of air from the crank case.

Within the sleeve 14 there is provided the usual or any preferred form of reciprocating piston 20 which in the present instance is provided with the usual packing rings 21 and 22 and in order that it may fit the upper constricted portion of the sleeve 14, without leaving too much clearance space between the piston and the head of the cylinder, the upper end of the piston is of smaller diameter so as to extend nearly to the head, substantially as illustrated in the drawings. The piston is connected by the usual pitman 23 with crank 24 of the shaft 25. The crank shaft 25 is supported in bearings 26 in the crank case 2 in the usual or any preferred manner, the crank case being in the present instance, sealed or made air tight so that air admitted thereto may be compressed therein by the reciprocation of the piston, such air being used for scavenging purposes as hereinafter described.

For the purpose of reciprocating the sleeve 14 I have preferably provided an ec-

centric gear mechanism connected with and operable by the crank shaft 25. To accommodate this mechanism the crank case is enlarged at 27 to inclose the mechanism. It will be understood, however, that any suitable arrangement of the mechanism relative to crank case may be made, to accomplish the desired result. The mechanism for reciprocating the sleeve as shown in Figs. 1, 2, 7 and 8 comprises an eccentric chain gear 28 secured to or integral with an eccentric 29, which carries an eccentric strap 30. The strap is connected to an arm or pitman 31 which extends upwardly and has pivoted at its outer end a stud or small shaft 32 which carries on one end thereof another eccentric 33. The stud or shaft 32, on the opposite end thereof has secured thereto a chain gear 34 which is twice the diameter of the chain gear 28, and is connected with the latter by means of a toothed chain 35 the arrangement being such that it will require two revolutions of the crank shaft 25 for one rotation of the gear 34, and the eccentric 33 connected therewith. A strap 36 surrounds the eccentric 33 and is connected by means of an arm or pitman 37 with a pin 38 projecting from the side of the reciprocating sleeve 14 so as to reciprocate the latter in a predetermined manner when the shaft 25 rotates. For the purpose of preventing the arm 31 and the gear 34 and other parts connected therewith, from revolving with the shaft 25 and at the same time to permit the eccentric 29 to reciprocate the parts the side wall 27 of the crank case is provided with suitable means to permit such reciprocation. For this purpose, the side wall 27 is fitted with a slide track 39 in which a block 40 is adapted to slide, the block 40 being revolvably carried upon the end of the shaft 32, substantially as illustrated in Figs. 2 and 8. This double eccentric device, I have found, permits the reciprocation of the sleeve 14 to take place in the manner desired; and to illustrate graphically the movement of the sleeve during two complete revolutions of the crank shaft 25, I have shown across the tops of the drawings in Figs. 3-6, a dotted line and points indicated thereon at a, b, c, etc., to graphically represent the position of the sleeve at each quarter turn of the shaft.

The operation of my engine may be described as follows, in connection with Figs. 3-6, where Fig. 3 indicates the position of the piston and sleeve at the beginning of the intake stroke. The sleeve 14 is just starting toward its lowest extreme of movement to open the intake port, said port being closed by a slight reverse movement of the sleeve at the end of the inspiration stroke, which is indicated in Fig. 4 of the drawings. During compression the valves or ports all remain closed or substantially in the position indicated in Figs. 4 and 5, Fig. 5 indicating

the position of the parts at the end of the compression stroke. After the compression stroke comes the explosion which takes place when the ports are substantially in the position shown in Fig. 5. As indicated in Fig. 6 the sleeve 14 is moving upward toward the end of this stroke to bring the auxiliary exhaust ports and the scavenging air inlet ports into registry so that these will be exposed by the reciprocating piston. It will be noted in Fig. 6 that the plane of the auxiliary exhaust port 10, 17 is above the plane of the scavenger port 13, 19, so that exhaust gases, immediately after the explosion, will pass out through the auxiliary exhaust port before the scavenger port is open by the movement of the piston. As soon, however, as the scavenger port is opened, the air which has been compressed in the crank case, rushes in and assists in cleaning out the burned gases and this scavenging is further completed on the final up stroke by the opening of the exhaust port 8, as indicated in Fig. 1 of the drawings. During the up-stroke the remaining burned gases and scavenging air are forced out through the exhaust port 8 and the movement of the sleeve 14 is again changed so that the exhaust port is closed at the beginning of the intake stroke when the mechanism comes back to the position indicated in Fig. 3 of the drawings after having completed the 4-stroke cycle. As indicated in Fig. 6 of the drawings, the sleeve 14 is brought into position to open the air inlet valve 11, 18 so that during the upstroke or scavenging stroke of the piston 20, air is drawn into the crank case and finally released when the parts come into the position indicated in Fig. 6 at the beginning of the fourth cycle, as previously described.

It will be noted that the double eccentric mechanism for reciprocating the sleeve 14 is adapted to move the sleeve very quickly from one extreme of movement to another when the two eccentrics 29 and 33 are working together and to reciprocate the sleeve very little during the intermediate revolution of the crank shaft when the movements of the two eccentrics are practically in opposite directions. It is this double eccentric arrangement which facilitates moving the sleeve 14 in the desired manner.

It will be understood that various mechanisms comprising eccentric gears or other suitable devices may be employed to give the required movement to the sleeve 14 and in Figs. 9 and 10 I have illustrated another form of device adapted for this purpose. Referring to Figs. 9 and 10, 25 represents the crank shaft, which, in this instance, is provided with an eccentric 50 connected to and co-axial with a gear 51, the latter of which is adapted to mesh with a pinion 52 which is connected with a larger gear 53

adapted to mesh with an internal gear 54 carried by an eccentric strap connected with an arm or pitman 55, which latter by means of the pivotal opening at 56, may be connected with a suitable pin on reciprocating sleeve 14. The floating gears 52, 53 are pivoted on a pin 57 which projects from a bored out disk 58 which disk also surrounds the eccentric 50 as illustrated in Fig. 9. This disk 58 is preferably held in place by means of a plate 59 secured thereto by screws or other suitable device. It will be seen, in the sectional portion of Fig. 10, that the eccentric gear 51 as it rotates, will rotate the gears 52, 53 and these gears will rotate the disk 58 about the eccentric 50, since the internal gear 54 of the strap is prevented from rotation by arm 55. The proportions of the several gears are such that it requires two revolutions of the crank shaft 25 to bring the eccentrics and connected parts back to the same position. Thus we have in this construction the two eccentrics which at one time are acting together and at another time acting in opposition so that such a mechanism is adapted to give the two extremes a movement to the sleeve 14 as required by the location of the ports therein and in the fixed cylinder.

In engines of similar type it has been found that, during the explosion, the sleeves are subjected to an enormous pressure and, under such conditions, are difficult to move, for during the explosion the pressure is all on one side of the sleeve. In my device I have overcome any tendency of the sleeve to fly out of the cylinder when the explosion occurs, by providing the sleeve with a reduced area at its upper end, or that portion which is exposed above the piston in the explosion chamber at the time of the explosion of the gases. This construction is such that at the time of the explosion of the pressure of gases at X point Fig. 1 of sleeve 14 will be exactly the same pushing upward as the pressure of gases at the point Y of sleeve 14 pushing downward. As an example—if the area of the inside of the cylinder at Y is exactly the same as the area of the inside of the sleeve at X the gases will exert the same pressure against X to drive it away from the piston as it exerts against Y to drive it away from the cylinder head and the only pressure that is brought to bear upon the sleeve toward driving it out of the cylinder is that which is caused by the friction of the piston rings against the inner wall of sleeve 14. It is to be understood that the pressure exerted upon either side of the port opening 16 is balanced by a like pressure upon the other side.

Various modifications of the specific details or arrangement of the parts may be made, and the sleeve may be moved in various ways without departing from my invention as defined in the claims.

I claim—

1. In an internal combustion engine, the combination with a reciprocating piston and a crank shaft, of a stationary cylinder, the upper or explosion end of which is of reduced internal area and provided with intake and exhaust ports located in different planes, said reduced portion of the cylinder being also provided with two annular channels opening inwardly one above the exhaust port and the other between the exhaust port and the intake port, a reciprocating sleeve, between the piston and cylinder, the upper end of which is of reduced area to pass up within the reduced area of the cylinder, this reduced area of the sleeve being provided with ports in the same plane, said ports being adapted to register either with said exhaust or with said intake port in said cylinder, and means operable by said shaft for reciprocating said sleeve through two different extremes of movement alternating with each revolution of the shaft, for bringing the ports in said sleeve into registry with the intake and exhaust ports of said cylinder in predetermined sequence, said annular channels being adapted to permit balanced pressure on said sleeve.
2. In an internal combustion engine, the combination with a reciprocating piston, and a crank shaft, of a stationary cylinder having a reduced internal area at the upper end, just below the head, said reduced area being substantially of the same diameter as the outside diameter of the piston and provided with an intake port and an exhaust port located in different planes, said reduced portion of the cylinder being also provided with an annular channel, opening inwardly, between the head and the exhaust port, and another annular channel, opening inwardly, between the exhaust port and the intake port; said cylinder having an auxiliary exhaust port near the lowest point reached by the piston, a scavenging port at the lowest point reached by the piston and an air inlet port at a point below the scavenging port; a reciprocating sleeve fitting closely within said cylinder and outside of said piston, with a reduced outside area at the upper end fitting closely in the aforesaid reduced internal area of the said fixed cylinder and provided with ports in the same plane adapted for registry with said sleeve being also provided in the lower portion thereof with auxiliary exhaust, the scavenging and air inlet ports adapted for registry respectively with the auxiliary exhaust, scavenging and air inlet port in said cylinder and means operable by said shaft for reciprocating said sleeve through two different extremes of movement alternating with each revolution of the shaft, for bringing the ports in said sleeve into registry with said ports in said fixed cylinder in pre-

determined sequence, said annular channels being adapted to permit balanced pressure on said sleeve.

3. In an internal combustion engine, the combination with a reciprocating piston and a crank shaft of a stationary cylinder, the upper end of reduced inside area provided with intake and exhaust ports located in different planes said cylinder being provided with annular channels opening inward one above the exhaust port and one between the exhaust and the intake ports, a reciprocating sleeve, between the piston and said cylinder, the upper outside area reduced to pass up snugly within the reduced inside area of the aforesaid cylinder, provided with a plurality of ports in the same plane adapted to cooperate with either the intake or exhaust ports or to lie over the annular channel between the exhaust and intake ports, packing rings on each side of said plurality of ports in said sleeve and means for reciprocating said sleeve through different extremes of movement alternating with each revolution of the shaft, one extreme of movement being adapted to bring said ports in the sleeve into registry with said exhaust and intake ports respectively and the other to keep them in communication with the lower annular channel, said annular channels being adapted to permit balanced pressure on said sleeve.
4. In an internal combustion engine, the combination with a reciprocating piston and a crank shaft, of a stationary cylinder, provided with an integral head, the upper or explosion end just below the head being of reduced internal area and provided with intake and exhaust ports located in different planes and two annular channels opening inwardly, one above the exhaust port and one between the exhaust and the intake port, said stationary cylinder being connected with a closed crank case and provided with a bypass communicating with the crank case and with a scavenging port in said cylinder, of a reciprocating sleeve fitting closely within said cylinder and outside of said piston provided with a reduced outside area at the upper end fitting closely within the aforesaid reduced internal area of the fixed cylinder and provided with ports in the same plane adapted for registry with said intake and said exhaust ports in said cylinder and a scavenging port adapted for registry with said scavenging port in said fixed cylinder to permit entrance of air from the crank case for scavenging purposes in said cylinder and means, operable by said crank shaft, including an eccentric and eccentric pinion fastened to said shaft, intermediate gearing and a pitman for reciprocating said sleeve alternately through two different extremes of movement for bringing the ports in said sleeve into registry respectively with the corresponding ports in said cylinder in pre- 130

determined sequence, substantially as described.

5. In an internal combustion engine, the combination with a reciprocating piston, a 5 crank shaft and a stationary cylinder provided with intake and exhaust ports located in different planes and an annular channel between said ports, of a reciprocating sleeve 30 between the piston and said cylinder, provided with a plurality of ports, in the same plane, adapted to cooperate with either the exhaust or intake ports or with said annular channel, packing rings on each side of said 35 plurality of ports in said sleeve and means for reciprocating said sleeve alternately through two different extremes of movement, one extreme of such movement being adapted to bring said ports in the sleeve into registry with said exhaust and intake ports respectively and the other to keep them in communication with said annular channel.
- 10 5. In an internal combustion engine, the combination with a reciprocating piston, a 5 crank shaft and a stationary cylinder provided with intake and exhaust ports located in different planes and an annular channel between said ports, opening inward, of a reciprocating sleeve between the piston and 10 said cylinder, provided with a plurality of ports in the same plane adapted to coöperate with either the exhaust or intake ports or to lie over said annular channel and means, 15 operable by said shaft, for reciprocating said 15 sleeve to bring said ports therein into the plane of the exhaust port of said cylinder, then into the plane of the intake port for registry therewith respectively during one revolution of said shaft and for holding said 20 ports in the sleeve in communication with said annular channel during the succeeding revolution of said shaft, whereby, during the 20 explosion, the pressure on said sleeve will be balanced.
- 25 6. In an internal combustion engine, the

combination with a reciprocating piston, a crank shaft and a stationary cylinder provided with intake and exhaust ports located in different planes and an annular channel between said ports, of a reciprocating sleeve 30 between the piston and said cylinder, provided with a plurality of ports, in the same plane, adapted to cooperate with either the exhaust or intake ports or with said annular channel, packing rings on each side of said 35 plurality of ports in said sleeve and means for reciprocating said sleeve alternately through two different extremes of movement, one extreme of such movement being adapted to bring said ports in the sleeve into registry with said exhaust and intake ports respectively and the other to keep them in communication with said annular channel.

In testimony whereof I have hereunto set my hand in the presence of two subscribing 45 witnesses.

CHARLES A. GASS.
